UNITED STATES PATENT OFFICE

JACKSON T. BERGER, OF SPOKANE, WASHINGTON

WINDOW CONSTRUCTION

Application filed August 28, 1931. Serial No. 559,832.

My present invention relates to improvements in window construction which involves combinations and arrangements of parts in the frame structure and in the vertically sliding sashes guided therein, whereby the parts may be manufactured at comparatively inexpensive cost of production; the parts may be assembled and the units installed with facility; and a durable and strong window structure is assured. The frame is provided with interchangeable parts in order that it may accurately be fitted in various types of wall structures or building-wall openings, and in all of the arrangements and installations, weather tight joints are provided between the sashes and the frame, and between the frame and the building wall.

Means are provided for vertically adjusting and retaining the slide sashes in adjusted position and the employment of box frames, sash pulleys and ropes, and sash weights is avoided, thereby materially reducing the cost of manufacture of the window structures.

Means are also provided whereby the upper and lower sashes may bodily be removed from the window frame in order to render accessible the outer sides of the sashes from the inner side of the window, to permit washing and cleaning of the outer sides of the sashes, painting the exteriors of the sashes, and for other purposes.

The invention consists in certain novel combinations and arrangements of parts as will hereinafter be more fully set forth and claimed. In the accompanying drawings I have illustrated one complete example of the physical embodiment of my invention wherein the parts are combined and arranged according to the best mode I have thus far devised for the practical application of the principles of my invention.

Figure 1 is a perspective view in vertical section showing the sashes in closed position in the window frame.

Figure 2 is a vertical sectional view through the sashes and frame, and indicating by dotted lines the manner of tilting or swinging inwardly the two sashes of the window.

Figure 3 is a horizontal sectional, detail view showing one side of the frame and sash,

with the parts installed in a brick-veneer building wall, and the interior finish for the frame comprises a plaster return in lieu of wood trim.

Figure 4 is a view similar to Figure 3 with the frame secured in the opening of the wall of a frame or weather-boarded house and the interior finish comprising a plaster return to the window frame.

Figure 5 is an enlarged sectional view showing the window structure in the opening of a wall of a frame house with exterior wood trim, and also interior wood trim about the window frame.

Figure 6 is a cross sectional view of one of the metal sash-carrier-plates, and indicating by dotted lines an expanded arrangement of the plate.

Figure 7 is a perspective view of one of the pair of carrier-plates used with each frame and pair of sashes.

Figure 8 is an enlarged sectional view showing the weather proof joint between the lower rail of the upper sash and the upper rail of the lower sash. Figure 8a is a similar view of a modified form of weather proof joint for these sashes.

Figure 9 is a sectional detail view of one of the combined sash fasteners and lifters, as at line 9—9 of Figure 10, and Figure 10 is a face view of one of the sash fasteners and lifting loops, two of which are mounted on each window sash.

In carrying out my invention I preferably construct the window structure of wood with a sill 1 and an interior apron 2, the parts being provided with tongue and groove joints as indicated in Figs. 1 and 2, and the side stiles 3 and 4 of the frame are rigidly secured to the sill. A cross head 5 completes the rigid rectangular frame, and to this cross head are attached the upper cross plates 6 and 7 at the exterior and 6' at the interior side of the frame, tongue and groove joints being shown between the parts. At the exterior of the stiles, side rails are attached and indicated as 8, and the outer edges of the stiles are fashioned with tongues 9 that are fitted into complementary grooves 10 of the side rails to insure weather tight joints. As seen in Fig.

ure 5 an additional, shallow groove 10a is provided in the inner face of the side rails at one side of the grooves 10.

The exterior trim for the window frame 5 may include finishing strips of molding as 11 and 12, at the sides of the frame, and a horizontal molding strip 12' is employed for finishing the top part of the frame.

Each window frame is equipped with a 10 pair of metal carrier-plates 13 and 14, and these plates, at their lower ends, are provided with pivot holes 15 located just above the squared lower end of the plate which is indicated as 16. Pivot pins or bolts 17, which 15 pass through the holes 15, are secured to in the side stiles 3 and 4 of the frames, and the corners 18 at the inner sides of the carrier plates are cut on curves having the pivot pins for centers, to permit inward swing of the 20 plates on these pivots as centers.

At their upper ends the carrier plates are fashioned with a hole 19, for an attaching screw 20, or other suitable device, and the plates are each fashioned with a pair of parallel tongues 21 and 22 extending the full height or length of the plates.

The plates may be fashioned from suitable sheet metal adapted to lie flat against the sides of the side stiles 3 and 4, and the bodies 30 of the plates may be of concavo-convex shape as indicated by dotted lines in Figure 6, or flat, and the tongues 21 and 22 that are fashioned by crimping or folding the metal, may be flat, as indicated by full lines, or they may 35 be of V-shape in cross section as indicated by dotted lines. When the V-shape is employed the carrier plates are preferably fashioned from resilient metal and these V-shapes more adequately provide for a weather proof joint 40 in the window structure.

As best seen in Figure 7 each of the carrier plates is fashioned with semi-circular depressions or notches 23 in the edges of the two tongues 21 and 22, for co-action with a latch- 45 device by means of which the upper sash 24 and the lower sash 25 may be retained in vertically adjusted position.

Each of the sashes, at its opposite side edges, is provided with a vertical groove 26, 50 and these grooves fit over the pairs of tongues 21 and 22 of the two carrier plates, and the tongues and grooves co-act in retaining the sashes in upright position and in guiding the sashes as they are raised or lowered.

Both of the sashes are vertically adjustable 55 and a pair of latch devices are provided for each sash to hold the sash in adjusted position, and to fasten the sash in its selected position. Each latch device or sash fastener 60 comprises a latch bolt 27 having a circular head 28 complementary to the notches 23 of the carrier plates, and a push button 29, the latter being accessible from the interior side of the window sash to slide the bolt in its 65 housing 30 against the tension of a spring 31.

The housing is secured in a socket S of the sash, that intercepts the groove 26 of the sash, and a cover plate 32 is secured by screws 33 to the face of the sash to retain the spring under tension. The spring is interposed between the housing and a washer 32' on the slide bolt and the spring normally holds the bolt in position for its head 28 to seat in the notch 23 of the tongue of the carrier plate. By pushing in on the button 29 the head is removed from the notch and then the sash is free to be raised or lowered. For convenience in raising or lowering the sash, the cover plate is fashioned with an integral finger ring or loop 70 75 80 85 90 95 100 105 110 115 120 125 130 135 140 145 150 155 160 165 170 175 180 10120 10125 10130 10135 10140 10145 10150 10155 10160 10165 10170 10175 10180 10185 10190 10195 10200 10205 10210 10215 10220 10225 10230 10235 10240 10245 10250 10255 10260 10265 10270 10275 10280 10285 10290 10295 10300 10305 10310 10315 10320 10325 10330 10335 10340 10345 10350 103

The presence of the tongue and groove throughout the structure, as indicated at 43 and 44 in Figures 1 and 2 where the tongue and groove joint is used between the upper 5 rail of the upper sash and the under face of the cross head 5 of the window frame, insures whether tight joints between parts of the frame, and also between the frame and the sashes.

10 In Figure 2 the sashes are shown in dotted position after the screw 20 has been released from the top of the carrier plates, and the two carrier plates and two sashes have been swung inwardly on the pivots 17 at the lower 15 ends of the carrier plates.

To facilitate the bodily swinging movement of the carrier plates and the sashes, each of the plates is provided with an opening or hole 45 at its inner side, near the top edge of 20 the plate, and a cross bar with hooked ends may be fitted to these two holes of the plates to hold the plates as a rigid structure as they swing on their pivots, and to hold the plates rigidly while the outer faces of the sashes are 25 being cleansed, painted, or otherwise treated. After the carrier plates and sashes have been swung back into place with their outer edges fitted in the grooves 10a, the screws 20 are replaced, and the cross bar, or other tool is 30 removed and stored for future use.

The filler strip 40 of Figure 5 may be used in walls of various thicknesses, and while the thickness of the window frame remains the same in the various walls, the thickness 35 of the filler strip varies, in order to bring the interior trim out to the face of the plastered wall within the room. In Figures 3 and 4 the use of the standard window structure according to my invention is illustrated 40 with two walls of different thickness, the thicker wall in Figure 3 being of brick or stone veneer, and the wall of Figure 4 being that of a frame house. The plaster return P in both views terminates in the groove 39 45 of the side stiles, but the window recess of the thicker wall is deeper than that of the thinner wall, although both walls have the same thickness of window frame or structure.

50 Having thus fully described my invention, what I claim as new and desire to secure by Letters Patent is:

1. The combination with a window frame, of a pair of carrier plates mounted at opposite sides thereof, guide tongues on said plates, a pair of sliding sashes having grooves complementary to the tongues, and co-acting means on the sash and tongues for retaining the sash in adjusted vertical position.

60 2. The combination in a window structure with a pair of carrier plates having spaced parallel guide tongues, of a pair of sliding sashes having complementary grooves for the tongues, said tongues having each a series of spaced notches, sash fasteners on the

sashes, and said fasteners including spring pressed bolts for co-action with said notches.

3. The combination in a window structure with a pair of carrier plates having parallel guide tongues and notches in said tongues, of a pair of slidable sashes having grooves for the tongues, a pair of spring pressed slide bolts mounted in each sash, and a head on each bolt for engagement in a notch of a tongue.

4. The combination in a window structure with a pair of side stiles having exterior tongues and a cross head having a groove in its under face, of side rails having grooves fitted to said tongues and additional grooves in said rails, a pair of carrier plates having pivotal supports on said stiles and their outer edges fitted in said additional grooves, and a pair of sliding sashes mounted on said plates.

5. The combination with a window frame including spaced, grooved rails, of a pair of carrier plates having pivotal connections at their lower ends to said frame and detachable fastenings at the upper ends of said plates, said plates each having a guide tongue at its inner edge, the inner edges of the plates fitted in said grooved rails, a second tongue on each plate intermediate its inner and outer edges, and an upper and lower sash having side grooves for co-action with said tongues.

In testimony whereof I affix my signature.
JACKSON T. BERGER.
